UNITED STATES PATENT OFFICE

MICHEL P. VUCASSOVICH, OF GLOUCESTER, MASSACHUSETTS

FREEZING APPARATUS

Application filed May 27, 1930. Serial No. 456,144.

This invention relates to apparatus for freezing fish and other comestibles, adapted to practice a method which consists in establishing a moving liquid having a freezing point below that of the material to be frozen, and with a movement from a loading point to a discharging point, said liquid having a temperature below the freezing point of the material, arranging said material in buoyant receptacles, and subjecting the receptacles to movement through the flow of the liquid, and to the temperature of the liquid as it is moved.

Said apparatus comprises a substantially horizontal container internally partitioned to form a sinuous runway which includes elongated major portions extending side by side, and shorter neck portions connecting the major portions in pairs, the runway being adapted to conduct a moving refrigerating liquid and buoyant receptacles floating therein and charged with material to be frozen, in a sinuous path from a loading point at one end of the runway to a discharge point at the opposite end. Heat from charges in the receptacles is transferred downward through the bottoms of the receptacles to the moving body of the liquid, causing freezing to commence at the lower sides of the charges and progress upwardly. The receptacles are provided with covers constituting deflectors for a refrigerating liquid discharged thereupon.

The apparatus comprises also means for discharging a refrigerating liquid upon the receptacle covers, so that heat is transferred upward from the charges through the covers to the refrigerating liquid discharged thereupon and deflected thereby.

The present invention is characterized by certain improvements in the buoyant receptacles, whereby the upward transference of heat from the charges is facilitated by causing it to pass through metal instead of passing through air in the receptacles, and whereby the charges are shaped before freezing, to a convenient form for marketing.

Of the accompanying drawings forming a part of this specification,—

Figure 1 is a fragmentary top plan view, showing a portion of the apparatus, the cover of the container being removed.

Figure 2 is a section on line 2—2 of Figure 1, showing the container cover.

Figure 3 is a section on line 3—3 of Figure 2.

Figure 4 shows in perspective one of the heat conducting inner covers hereinafter described.

Figure 5 shows in perspective one of the open molds shown in section by Figure 3, and a charge therein.

The same letters of reference indicate the same parts in all of the figures.

In the drawings, 1 designates a substantially horizontal container or tank, having a cover 5 and integral partitions 2, forming a sinuous runway composed of elongated major portions 3, located side by side, and shorter neck portions 4, connecting the major portions.

The inlet end 6 of the runway is extended to one end of the container to form a loading end, and the opposite end 6a is extended to a point adjacent the loading end to form a discharge end.

A liquid such as brine, having the desired temperature, is delivered through a pipe 7, and discharged through an overflow pipe 8, said pipes maintaining a constant level of the liquid at a predetermined height.

Buoyant metallic receptacles 9 are provided, adapted to contain charges 10 of material to be frozen, and to be moved by the liquid in the runway from the end 6 to the end 6a.

Heat is transferred downward from the charges 10 through the bottoms of the receptacles, to cause the freezing of the charges to progress from their bottom surfaces upward.

The containers include flat bottoms on which the charges rest and curbs 9a upstanding from the bottoms. Metallic covers 15 rest on the curbs and have marginal flanges 15a surrounding the curbs. The upper surfaces of the covers are adapted to deflect refrigerating liquid discharged thereupon.

Conduits 13 supported above the runway are adapted to discharge a refrigerating liquid upon the deflecting covers, and thereby subject the receptacles and their charges to

the temperature of the discharged liquid, said temperature being practically the same as that of the moving liquid in the runway. Heat is therefore transferred upward from the charge 10 through the deflecting covers to the liquid discharged thereon, causing the freezing of the charges to progress from their upper surfaces downward.

The present invention is characterized by 10 the hereinafter described improvements in and relating to the receptacles, said improvements being intended to facilitate the upward conduction of heat, and to impart a predetermined form to the charges, differing 15 from the internal form of the receptacles.

I provide each receptacle with a metallic inner cover 17, preferably of aluminum and adapted to bear on and impart a predetermined form to the surfaces of the charges 10. 20 The inner covers 17 are removably inserted in the receptacles and contact with the top surfaces of the charges, and with the receptacle curbs 9a, as shown by Figure 3.

Heat is conducted from the charges to the 25 refrigerating liquid impinging on the deflecting covers 15, through the metallic conducting parts provided by the inner covers 17, the curbs 9a, and the deflecting covers 15. The metal of said parts is adapted to conduct 30 heat more rapidly than the air in the spaces between the charges and the deflecting covers 15.

The charges 10 are preferably packed in frames 20, constituting open molds adapted 35 to impart a predetermined form to the margins of the charges. For example, each mold and the charge packed therein, may have a rectangular marginal form, as shown by Figure 5. The mold may be of metal, and in that 40 case heat is conducted through its sides, so that freezing occurs from the sides inwardly.

The molds are adapted to rest loosely, with the charges, on the bottoms of the receptacles, and their upper edges are preferably in 45 planes parallel with said bottoms and flush with the upper sides of the charges. The inner covers 17 are adapted to bear on the frames and constitute mold members, whereby a predetermined form is imparted to the 50 top sides of the charges, a corresponding form being imparted at the same time to the bottom sides of the charges by the bottoms of the receptacles 9. Each frozen charge may, therefore, have a rectangular form convenient for packing, transporting, and selling.

The charges may be wrapped in sheet material, such as cellophane, when they are 55 placed in the molds. If desired, each charge may be composed of a plurality of units separately wrapped and all formed in the same mold, as indicated by Figure 5, by the division lines 21.

60 The charges may be of fish in fillet, or other

form, beef, or other meat, or any comestible which may be advantageously molded and frozen in the manner described.

It is obvious that the charges may entirely cover the bottoms and contact with the curbs of the receptacles 10, in which case the open molds 20 will not be employed, the form of the bottom surfaces and margins of the charges being determined by the bottoms and curbs of the receptacles. Such form would not be as desirable, however, as the form imparted when the open molds are employed.

I claim:

1. A freezer as an element of freezing apparatus, comprising a buoyant metallic receptacle adapted to float in refrigerating liquid and to contain the material to be frozen, having a bottom, a rising curb at the boundaries of said bottom, a cover overlapping said curb to deflect falling liquid from the interior of the receptacle, and a metallic inner cover of high heat-conductivity spaced from said bottom and in heat conducting contact with said curb, adapted to transfer heat to the surrounding liquid from the upper side of a mass of material confined between said inner cover and bottom.

2. A freezing apparatus element comprising, in combination, a buoyant receptacle including a bottom and a curb adapted to be supported by a body of refrigerating liquid, a deflecting outer cover adapted to spread downwardly discharged refrigerating liquid over the space enclosed by said bottom, curb, and outer cover, and an inner cover spaced above the bottom and in heat conducting relation to the receptacle, said bottom constituting a lower mold member adapted to transfer heat to the supporting liquid, said inner cover constituting an upper mold member through which heat may be transferred to the curb preparatory to transference by the curb to the outer cover and to liquid discharged thereon.

3. A freezing apparatus element comprising, in combination, a buoyant metallic receptacle including a bottom, a curb and a deflecting outer cover, and a metallic inner cover bearing on the receptacle curb and spaced from the bottom.

4. A freezing apparatus element comprising, in combination, a buoyant metallic receptacle including a bottom, a curb, and a deflecting outer cover, an open mold bearing loosely on the receptacle bottom, and a metallic inner cover bearing on the mold, and on the receptacle curb.

5. An element of freezing apparatus comprising a receptacle of liquid-impervious, heat-conducting material having a bottom and an upstanding curb, adapted to be immersed to a greater or less extent in liquid refrigerant, a mold within said receptacle resting on the bottom thereof adapted to contain

the goods to be frozen, and a cover of heat-conducting material overlying said mold to rest and press on the goods therein, and being in heat-conducting contact with the curb of the receptacle.

In testimony whereof I have affixed my signature.

MICHEL P. VUCASSOVICH.
